(57) **ABSTRACT**

This invention relates to a new and distinct variety of strawberry plant named 'SB_12_53-118'. This new strawberry plant named 'SB_12_53-118' is primarily adapted to the growing conditions of West Central Florida, and is primarily characterized by its achenes typically set level with the surface of the fruit, good fruit flavor with firm flesh, large fruit, early time of first flower and fruit, moderate resistance to angular leaf spot; and vigorous plant.

4 Drawing Sheets

1

Latin name of the genus and species of the plant claimed:
Fragaria ananassa.

Variety denomination: 'SB_12_53-118'.

BACKGROUND

The present invention relates to a new and distinct strawberry variety named 'SB_12_53-118'. This new variety is a result of a controlled cross made in 2012 in an ongoing breeding program between strawberry variety designated 'Florida Radianc' (U.S. Plant Pat. No. 20,363) as the seed (female) parent, and the unreleased, unpatented strawberry breeding selection designated 'BG-5.321' as the pollen (male) parent. The variety is botanically known as *Fragaria ananassa*.

The seedling resulting from the aforementioned cross was selected from a controlled breeding plot in Hillsborough County, Fla. in the fall/winter of 2013-2014. After its selection, the new variety was asexually propagated by stolons in both Siskiyou County, Calif. and San Joaquin County, Calif. The new variety was extensively tested over the next several years in fruiting fields in Hillsborough County, Fla. This propagation has demonstrated that the combination of traits disclosed herein as characterizing the new variety are fixed and remain true-to-type through successive generations of asexual reproduction.

SUMMARY

'SB_12_53-118' is primarily adapted to the climate and growing conditions of West Central Florida. The subtropical

2

climate of West Central Florida provides the day length and moderate temperatures needed to produce an early yielding, vigorous plant and maintain fruit quality during the fall and winter production months.

5 The following traits have been repeatedly observed and are determined to be unique characteristics of 'SB_12_53-118', which in combination distinguish this strawberry plant as a new and distinct variety:

- 10 1. Achenes typically are set level with the surface of the fruit;
2. Good fruit flavor with firm flesh;
3. Large fruit;
4. Early time of first flower and fruit;
15 5. Moderate resistance to angular leaf spot; and
6. Vigorous plant.

20 'Florida Radianc' (U.S. Plant Pat. No. 20,363) has been a dominant strawberry variety in Hillsborough County, Fla. for more than ten years. The fruit of 'SB_12_53-118' are similar in flavor and firmness to its seed parent, 'Florida Radianc', but the fruits of 'SB_12_53-118' are greater in size, and more uniform and conical in shape during the early season. The achenes of 'Florida Radianc' are more sunken than those of 'SB_12_53-118'. In side-by-side comparisons from the 2017-2018 season (Nov. 11, 2017 to Feb. 23, 2018) and the 2018-2019 season (Nov. 15, 2018 to Feb. 27, 2019), 'SB_12_53-118' compares with 'Florida Radianc' (U.S. Plant Pat. No. 20,363) in the following combination of characteristics as described in Table 1.

TABLE 1

Characteristic	'SB_12_53-118'	'Florida Radiance' (U.S. Plant Pat. No. 20,363)
2017-2018		
November marketable yield (gm/plt)	41.7	29.7
December marketable yield (gm/plt)	59.3	23.7
January marketable yield (gm/plt)	84.5	110.4
February marketable yield (gm/plt)	254.5	203.9
Season marketable yield (gm/plt)	440.0	367.7
Season average berry size (gm)	29.9	25.5
Flavor	Good	Good
2018-2019		
November marketable yield (gm/plt)	49.4	27.0
December marketable yield (gm/plt)	34.1	23.8
January marketable yield (gm/plt)	79.4	49.7
February marketable yield (gm/plt)	237.2	394.5
Season marketable yield (gm/plt)	400.0	495.1
Season average berry size (gm)	33.2	34.5
Flavor	Good	Good

For identification, a series of molecular markers have been determined for this new variety.

'SB_12_53-118' differs from its parents, 'Florida Radiance' and 'BG-5.321' by the following combination of characteristics as described in Tables 2 and 3.

TABLE 2

Characteristic	'SB_12_53-118'	'Florida Radiance' (U.S. Plant Pat. No. 20,363)
Fruit: Early season berry size	Large	Medium to large
Fruit: Early marketable yield	Medium to high	Medium
Plant: vigor	High	Medium to high
Fruit: seed position	Even with surface	Moderately sunken

TABLE 3

Characteristic	'SB_12_53-118'	'BG-5.321'
Fruit: size	Large	Very large
Fruit: marketable yield	Ranges from medium to high	Medium
Fruit: Color	Medium red	Light to medium red

BRIEF DESCRIPTIONS OF THE DRAWINGS

The accompanying color photographs illustrate the overall appearance of typical specimens of the new strawberry variety 'SB_12_53-118' at various stages of development, as true as it is reasonably possible with color reproductions of this type. Color in the photographs may differ slightly from the color value cited in the botanical descriptions which accurately describe the color of 'SB_12_53-118'. The depicted plant and plant parts of the new strawberry variety 'SB_12_53-118' are approximately five months old. The photographs were taken in Hillsborough County, Fla.

FIG. 1 shows typical fruiting field characteristics of 'SB_12_53-118', taken in the month of March 2020;

FIG. 2 shows a close-up view of a typical plant of 'SB_12_53-118', taken in the month of March 2020;

FIG. 3 shows typical mature and immature field fruit of 'SB_12_53-118', taken in the month of March 2020; and

FIG. 4 shows typical internal and external mature fruit characteristics of 'SB_12_53-118', taken in the month of March 2020.

DETAILED BOTANICAL DESCRIPTION

The new variety 'SB_12_53-118' has not been observed under all possible environmental conditions. The characteristics of the new variety 'SB_12_53-118' may vary in detail, depending upon variations in environmental factors, including weather (temperature, humidity and light intensity), day length, soil type and location. In addition, the characteristics of any parental variety or comparison variety included in Tables 1, 2 and 3 of the present invention may vary in detail, depending upon variations in environmental factors, including weather (temperature, humidity and light intensity), day length, soil type and location.

The aforementioned photographs, together with the following description of the new variety 'SB_12_53-118', unless otherwise noted, are based on observations taken during the 2019-2020 growing season in Hillsborough County, Fla. These measurements and ratings were taken from plants of 'SB_12_53-118' dug from a high-elevation nursery located in Siskiyou County, Calif. during mid-September 2019 and planted approximately four to five days later in Hillsborough County, Fla. The approximate age of the observed plants is five months. Yield observations including average weight and marketable yield, along with fruit quality characteristics including soluble solids, are averaged from four years of data collected from the 2015-2016 through 2018-2019 growing seasons. Flower measurements and characteristics are from secondary flowers unless otherwise noted. Fruit characteristics and measurements are from secondary fruit, unless otherwise noted.

Where noted, color terminology follows The Royal Horticultural Society Colour Chart, London (2007).

The following characteristics describe fruit, plant, stolon, foliage, fruiting truss, flower, reproductive organs and pest and disease characteristics of the new strawberry 'SB_12_53-118'.

Fruit characteristics:

Color of mature fruit.—RHS 45A (red).

Color of internal flesh (excluding core).—RHS 44A (medium red).

Color of core.—RHS 44C (medium red).

Average length (cm).—3.8.

Average width (cm).—3.4.

Size.—Large.

Average length/width ratio.—1.13 (ranges from as long as broad to slightly longer than broad).

Average calyx diameter (cm).—4.1.

Season average weight (gm).—31.8.

Achene color, shaded side.—RHS 153C (yellow green group).

Achene color, sun-exposed side.—RHS 185A (greyed purple group).

Average achene weight (mg).—0.6.

Average achenes per berry.—274.0.

Average achene length (mm).—1.5.

Average achene width (mm).—0.9.

Season marketable yield (gm/plant).—459.4.

Predominant shape.—Cordate (cordiform).

Difference in shape between primary and secondary fruit.—Ranges from moderate to large.

Band without achenes.—Narrow.

<i>Evenness of surface</i> .—Ranges from slightly uneven to strongly uneven.		<i>Average length (cm)</i> .—10.1.
<i>Evenness of color</i> .—Even.		<i>Average width (cm)</i> .—13.0.
<i>Glossiness</i> .—Ranges from medium to strong.	5	<i>Average area foliage (cm²)</i> .—133.6.
<i>Insertion of achenes</i> .—Even with surface.		<i>Shape in cross section</i> .—Slightly concave.
<i>Position of calyx attachment</i> .—Inserted.	5	<i>Texture/interveinal blistering</i> .—Moderate.
<i>Attitude of sepals</i> .—Outward.		<i>Leaf glossiness</i> .—Ranges from medium to strong.
<i>Size of calyx in relation to fruit diameter</i> .—Slightly larger.	10	<i>Leaf variegation</i> .—Absent.
<i>Adherence of calyx (when fully ripe)</i> .—Strong.		<i>Venation pattern</i> .—Pinnate.
<i>Firmness of flesh</i> .—Firm.		<i>Apex descriptor</i> .—Obtuse.
<i>Distribution of red color of the flesh</i> .—Continuous from margin to center.		<i>Petiole characteristics</i> :
<i>Hollow center expression</i> .—Moderate.	15	<i>Petiole color</i> .—RHS 144B (yellow green group).
<i>Average cavity length (mm)</i> .—26.3.		<i>Average length (cm)</i> .—15.5.
<i>Average cavity width (mm)</i> .—4.3.		<i>Average diameter (mm)</i> .—3.3.
<i>Flavor</i> .—Good.		<i>Petiolule color</i> .—RHS 144B (yellow green group).
<i>Soluble solids (% Brix)</i> .—6.3.		<i>Petiolule average length (mm)</i> .—8.2.
<i>Time of first flowering</i> .—Early (mid-October in Hillsborough County, Fla.).	20	<i>Average petiolule diameter (mm)</i> .—1.7.
<i>Flowering season</i> .—October-February.		<i>Attitude of hairs</i> .—Strongly outward.
<i>Time of first fruit</i> .—Early (mid-November in Hillsborough County, Fla.).		<i>Texture</i> .—Moderate to smooth.
<i>Fruiting season</i> .—November-March.	25	<i>Frequency of bract leaflets</i> .—Ranges from few to none (33% occurrence).
<i>Harvest period</i> .—Mid-November to March (in Hillsborough County, Fla.).		<i>Size of bract leaflets</i> .—Small to absent.
<i>Post harvest fruit longevity</i> .—9-11 days if stored according to industry standards.		<i>Pubescence</i> .—Ranges from light to moderate.
<i>Type of bearing</i> .—Not remontant.	30	<i>Stipule characteristics</i> :
Plant characteristics:		<i>Color</i> .—RHS 145C (yellow green group).
<i>Average height (cm)</i> .—22.9.		<i>Anthocyanin coloration</i> .—RHS 56D (red group).
<i>Average spread (cm)</i> .—39.6.		<i>Anthocyanin intensity</i> .—Weak.
<i>Size</i> .—Medium to Large.		<i>Average length (mm)</i> .—70.25.
<i>Habit</i> .—Upright.		<i>Average width (mm)</i> .—11.58.
<i>Density</i> .—Medium.		<i>Base descriptor</i> .—Truncate.
<i>Vigor</i> .—Medium to High.		<i>Apex descriptor</i> .—Obtuse.
Stolon characteristics:		<i>Shape</i> .—Triangular.
<i>Color</i> .—RHS 144A (yellow green group).		<i>Margin</i> .—Smooth.
<i>Anthocyanin coloration</i> .—RHS 184A (greyed purple group).	40	<i>Texture</i> .—Moderate to smooth.
<i>Anthocyanin intensity</i> .—Ranges from medium to strong.		<i>Fruiting truss characteristics</i> :
<i>Pubescence</i> .—Dense.		<i>Anthocyanin coloration</i> .—RHS 177C (greyed orange group).
<i>Attitude of hairs</i> .—Slightly outward.	45	<i>Anthocyanin intensity</i> .—Very weak.
<i>Average quantity in nursery (per square foot)</i> .—4 to 5 (medium).		<i>Average length at maturity (cm)</i> .—19.8.
<i>Average diameter at the bract (mm)</i> .—3.1 (medium).		<i>Position relative to foliage</i> .—Level with.
<i>Average length (cm)</i> .—32.5.		<i>Flower quantity (average per plant season long)</i> .—20-30 (medium to high).
Terminal leaflet characteristics:	50	<i>Average fruits per truss</i> .—4.
<i>Color of upper surface</i> .—RHS 147A (medium yellow green).		<i>Pedicel attitude of hairs</i> .—Slightly outward.
<i>Color of underside</i> .—RHS 147B (yellow green group).		<i>Pubescence</i> .—Strong.
<i>Average length (cm)</i> .—7.8.		<i>Attitude at first pick</i> .—Prostrate.
<i>Average width (cm)</i> .—6.6.		<i>Average pedicel length (cm)</i> .—9.3.
<i>Average area terminal (cm²)</i> .—51.6.		<i>Average pedicel diameter (mm)</i> .—2.2.
<i>Average length/width ratio</i> .—1.17 (longer than broad).		<i>Pedicel texture</i> .—Moderate to smooth.
<i>Shape of base</i> .—Obtuse.		<i>Pedicel color</i> .—RHS N144C (yellow-green group).
<i>Margins (shape of teeth)</i> .—Obtuse (serrate to crenate).	60	<i>Average peduncle length (cm)</i> .—2.3.
<i>Average serrations per leaf</i> .—18.7.		<i>Average peduncle diameter (mm)</i> .—3.2.
Foliage characteristics:		<i>Peduncle texture</i> .—Moderate to smooth.
<i>Color of upper surface</i> .—RHS 147A (medium yellow green).		<i>Peduncle color</i> .—RHS N144C (yellow green group).
<i>Color of underside</i> .—RHS 147B (yellow green group).		<i>Flower characteristics</i> :
<i>Number of leaflets</i> .—3.	65	<i>Flower bud shape</i> .—Pyriform.
<i>Leaf size</i> .—Medium.		<i>Average flower bud length (mm)</i> .—18.5.

Petal margin.—Smooth.
Petal base.—Decurrent.
Petal texture.—Smooth.
Petal average length (mm).—10.6.
Petal average width (mm).—10.1.
Petal average length/width ratio.—1.05 (as long as
 broad).
Average petals per flower.—6.1.
Upper sepal color.—RHS 144A (yellow green group).
Lower sepal color.—RHS N144A (yellow green 10
 group).
Sepal shape.—Cuneate.
Sepal apex descriptor.—Obtuse.
Sepal margin.—Serrate.
Sepal texture.—Moderate to smooth.
Sepal average length (mm).—13.7.
Sepal average width (mm).—4.9.
Sepal average length/width ratio.—2.80.
Average sepals per flower.—12.5.
Calyx average diameter (mm).—31.2.
Size of calyx relative to corolla.—Larger.
Size of inner calyx relative to outer calyx.—Same.
Relative position of petals.—Overlapping.
 Reproductive organs:
Receptacle color.—RHS 148B (yellow green group). 25
Pollen color.—RHS 14A (yellow orange group).
Stamen.—Present.
Average filament length (mm).—2.6.
Filament color.—RHS 157B (green white group).

Average anther length (mm).—1.2.
Anther shape.—Ovoid.
Anther color.—RHS 21A (yellow orange color).
Average pistils per flower.—274.0.
Pistil length (mm).—0.5-1.5.
Style length (mm).—0-1.
Style color.—RHS 2B (yellow group).
Stigma diameter (mm).—<0.1.
Stigma shape.—Simple.
Ovary color.—RHS 1D (green yellow group).
Pollen amount.—Abundant.
 Disease and pest reactions:
Powdery mildew (Sphaerotheca macularis).—Moder-
 ately resistant.
 15 *Angular leaf spot (Xanthomonas fragariae)*.—Moder-
 ately resistant.
Botrytis fruit rot (Botrytis cinerea).—Moderately sus-
 ceptible.
Fusarium wilt (Fusarium oxysporum).—Susceptible.
Anthracnose crown rot (Colletotrichum fragariae).—
 Moderately susceptible.
Two-spotted spider mite (Tetranychus urticae).—Sus-
 ceptible.
Winter hardiness.—Moderate.

We claim:
 1. A new and distinct strawberry plant named 'SB_12_53-
 118', as herein described and illustrated.
